UNITED STATES PATENT OFFICE.

PRESTON WARE, JR., OF BOSTON, MASSACHUSETTS.

IMPROVEMENT IN BOOTS AND SHOES.

Specification forming part of Letters Patent No. 122,085, dated December 19, 1871.

To all whom it may concern:

Be it known that I, PRESTON WARE, Jr., of Boston, in the county of Suffolk and State of Massachusetts, have invented a new and useful Improvement in Boots and Shoes; and I do hereby declare the following to be a full, clear, and exact description thereof, which will enable those skilled in the art to make and use the same, reference being had to the accompanying drawing forming part of this specification, in which drawing—

Figure 1 represents a sectional side view of my invention. Fig. 2 is a transverse section of the same.

Similar letters indicate corresponding parts.

This invention relates particularly to an improvement in the manufacture of machine-made, double-soled, or cork-sole boots and shoes; and said improvement consists in the arrangement of a cushion in combination with the outer sole, the double or cork sole, the inner sole and the upper, in such a manner that said cushion, being pressed tightly to the upper between the inner sole and the stitched welt or outer sole, prevents water from passing in between it and the upper, while the cork or double sole protects the foot against dampness if the outer sole should get wet.

In carrying out my invention I prepare a cushion, A, by taking a piece, a, of calf-skin, by preference enameled, about twelve inches long and two inches wide, which I fold over a leather cord, b, about one-eighth of an inch in diameter, and adhere the calf-skin with gum shellac or other adhesive substance not soluble in water. When dry I sew a row of stitches through the folded leather close up to the cord. Instead of using a leather cord for the filling I sometimes use a cotton cord, felt, or a flat piece of leather; or the filling may be omitted entirely and a row of stitches made close to the fold. When the cushion has been thus prepared, I last the boot or shoe in the

usual manner, by preference on an iron-plated last; then I tack the cushion around the edge of the boot or shoe, with the corded edge next to the upper, E; then I fit the double or cork sole B nicely between the corded edges, bringing the edge of the cork sole close up to the cord, as shown in Fig. 2, and on the bottom surface of the cork sole I place a stitched welt, C, being made of a simple strip of leather, with stitches near its outer edge, said strip being so adjusted that the stitches project outside the corded edge and fasten the same, together with the double or cork sole and cushion, to the inner sole by means of a Townsend screw-machine; or by pegs, nails, or a McKay sewing-machine. Finally, I put on the outer sole D, and screw, peg, or sew through the whole. The cushion A being pressed tightly to the upper between the inner sole stitched welt and outer sole, prevents water passing between it and the upper, and being adhered together by shellac or other water-resisting substance it is prevented from absorbing moisture, and by the cork sole the foot is protected against dampness if the outer sole should get wet. It is obvious that for the cork sole a sole of any other desirable material can be substituted.

By my process a cork sole or double-sole boot or shoe can be produced at one-half the cost of an ordinary hand-sewed article, and my boots and shoes are equally handsome, comfortable and durable.

What I claim as new, and desire to secure by Letters Patent, is—

The cushion A, made as herein described, and arranged in relation to the cork or double sole B, stitched-welt C, and outer sole D, substantially in the manner set forth.

PRESTON WARE, JR.
